FARREL FOUNDRY AND MACHINE COMPANY, OF ANSONIA, CONNECTICUT, A COR-
PORATION OF CONNECTICUT.

RUBBER-MIXER.

1,356,691.

Specification of Letters Patent. Patented Oct. 26, 1920.

Application filed January 16, 1919. Serial No. 271,419.

To all whom it may concern:

Be it known that we, DAVID R. BOWEN and CARL F. SCHNUCK, both citizens of the United States, and both residing in Ansonia, county of New Haven, State of Connecticut, have invented certain new and useful Improvements in Rubber-Mixers, of which the following is a full, clear, and exact description.

10 In our application, Serial No. 270,837, we have shown and described a rubber mixer of the single cylinder type having improved provisions for the feeding in or charging of the different ingredients to be mixed, (which usually include rubber chunks of comparatively large size and filling material or pigment in the form of a powder), whereby the construction and operation of the machine are simplified and 15 20 the expulsion of powder from the casing during the mixing overcome to a large degree.

The present invention relates primarily to a machine of the duplex type having two parallel rotors arranged in chambers or cylinders that are in free communication with each other, and one of the main objects in view is the application of certain new principles of charging or feeding set forth in 25 30 the companion case to machines of this last mentioned type.

We aim to provide a very simple and efficient form of duplex machine, in which the rubber and powder can be fed into the mixing chamber by gravity in a very convenient way during the rotation of the rotors without creating an objectionable dust cloud. It is unnecessary to hold the mass against the rotating blades by means of a 35 40 piston or other pressure device, the employment of which is objectionable, by reason of the fact that when it is moved to the operative position, it displaces air in the mixing chamber and consequently forces some of the powder out of the casing through leaks or cracks, or into the rotor bearings.

45 Our machine is also provided with efficient means for preventing slippage of the rubber mass over the interior surface of the duplex chamber without useful work being done upon the same by the rotor blades.

To these and other ends the invention consists in the novel features and combina-

tions of parts to be hereinafter described and claimed.

55

In the accompanying drawings:

Figure 1 is a front elevation of a rubber mixer embodying our improvements.

Fig. 2 is a top plan view of the same.

Fig. 3 is an end elevation looking from 60 the left of Fig. 1 with certain parts omitted.

Fig. 4 is an enlarged section on line 4-4 of Fig. 2.

Fig. 5 is a section on line 5-5 of Fig. 1.

Fig. 6 is a section on line 6-6 of Fig. 2. 65

The machine selected for illustration comprises a casing 10 having a duplex mixing or working chamber consisting of inter- 70 75 80 85 90 95 100 105 communicating partly cylindrical chambers 11 between which lower and upper longi- tudinal ridges 12, 12^a are arranged. In each of the chambers or compartments 11 of the duplex chamber is a horizontal rotor 13 comprising a shaft with blades 14. In the form shown, each rotor has two blades, one being arranged in one end of the corresponding compartment 11 and the other being located in the other end of said compartment, said blades having working faces adapted to mash the material against the inner surface of the chamber side wall. The blades are arranged on the shaft at an angle and are diametrically located with respect to each other, so that the material is worked back and forth alternately from one end of the compartment 11 to the other as the rotor rotates, while being mashed or smeared against the side wall of the chamber so as to mix the ingredients thoroughly.

The rotors 13 rotate in opposite directions and the material is thrown back and forth from one chamber 11 to the other through the intervening somewhat narrower space between the ridges 12, 12^a that separate the two chambers. One of the rotors is driven by means of a large gear wheel 15 applied to one end of its shaft and at the opposite end of said shaft a pinion 16 is applied, meshing with a similar pinion 17 on the shaft of the other rotor so as to provide for the opposite rotation of the rotors. Each rotor shaft has suitable bearings in the heads 18, 19 of the mixing chamber. These heads are carried by end frames or standards 20 and 21 respectively and are adapted to be attached to the side wall of the casing

by means of bolts as shown. The side wall is divided vertically and longitudinally into two side sections 10^a, 10^b (Fig. 4) bolted together at the top by bolts 22. The casing 5 has a movable lower section 23, which in this case is hinged at 24, so as to provide a swinging discharge closure. The door is dropped down when it is desired to discharge the mixing chamber and when discharge is completed, the door is held in the closed position by any suitable means, such as a cam 25. Inasmuch as the arrangement of the door forms no part of our invention, it will not be necessary to describe it in 10 greater detail.

In accordance with our invention, means are provided whereby the material to be mixed, consisting for example of rubber chunks and powder, can be readily charged 20 by gravity into the mixing chamber during the rotation of the rotors. To this end, a charging opening is located in the end wall or head of the chamber, through which the material will readily pass into voids or areas 25 of low pressure at the rear faces of two or more of the rotor blades, arranged on different shafts, whence such material is taken up by the blades on further rotation and thoroughly mixed by the working faces of 30 the blades in connection with the inner surface of the side wall of the duplex chamber. In the form shown, the end wall or head 19 is provided with a charging opening 26 located at the upper part of the duplex chamber 35 above and between the rotor shafts. This charging opening is located at the lower inner part of a charging hopper 27, which can be conveniently formed by casting the same integral with the head 19. The 40 hopper 27 is open at the top and has an inclined wall over which the material slides in a downward and inward direction into the mixing chamber. The charging opening 26, in the particular form shown, is located at about the level of the rotor shafts, 45 as shown in Fig. 6. At the upper part of its inner side, the hopper is closed in by surfaces 10^c, 10^d of the sections 10^a, 10^b respectively. These surfaces 10^c, 10^d present a substantially upright inner wall for the hopper, 50 the charging opening 26 being located at the bottom of such inner wall, which as shown in Fig. 6, does not extend as far downward as the bottom of the hopper and, therefore, 55 leaves a charging space through which comparatively large chunks of rubber as well as the powder can be introduced.

In the operation of the mixer, the spaces at the rear faces of the rotor blades 14 are 60 not completely filled with material and in such spaces there exist voids or areas of low pressure caused by the rotation of the blades into which rubber and powder can be readily introduced through the charging opening 65 26. The rubber chunks and powder are sim-

ply dumped into the hopper 27, either together or in any desired sequence and such material slides down into the bottom of the hopper by gravity and passes into the end of the mixing chamber, either by gravity, or 70 by the agitation or drawing in action created by the rotating blades, or by both gravity and agitation. The material introduced into the duplex chamber passes partly into one of the compartments 11 and partly into the 75 other compartment, a portion of it being introduced behind the blade of one rotor, and another portion of it being introduced behind the corresponding blade of the other rotor.

When the treated mass has become plastic and homogeneous, the machine can be discharged by opening the door 23 or in any other suitable manner.

One of the important advantages of our 85 invention is that it provides means for feeding in the material in a very simple and convenient manner without the use of any follower to maintain the material in contact with the blades. The blades operate on the 90 material by mashing or smearing it against the side walls of the compartments. These compartments present large working surfaces which are substantially continuous throughout their length, there being no interruption of said surfaces intermediate the 95 ends of the chamber for providing a charging opening, as has heretofore been customary. The charging opening is conveniently located at the end of the chamber, rather 100 than in the side wall, and no special means is necessary for forcing the material into the chamber through the charging opening. Escape of the material being treated is prevented by the blades adjacent the charging 105 opening, which blades force the material inwardly and draw it away from the charging opening. While the blades on the right hand ends of the rotors, as shown in Fig. 5, 110 force the material toward the charging opening, their action is neutralized by the left hand blades, which take up the material and force it back again into the right hand end of the duplex chamber before it can pass to the charging opening. The powder can be 115 quickly and directly incorporated with the rubber by our arrangement, but if a cloud of dust is created inside the mixer before the powder is fully incorporated in the mass, such dust is drawn away from the charging 120 opening by the rotating blades and is not expelled therefrom to any objectionable extent.

In the particular form shown, the width of the charging opening is somewhat greater 125 than the space between the rotor shafts in the mixing chamber. In the center, the charging opening is not as deep as it is on the sides, owing to the provision of the ridge 12^a on the upper part of the chamber.

In order to prevent slippage of the mass on the interior surfaces of the compartments 11, which would result in no useful work being performed by the rotors, we 5 prefer to mount the rotors in a special manner, and preferably each rotor blade is movable toward and away from the coöperating inner surface of the chamber to obtain a varying grip on the material as the blade 10 rotates. In the particular form shown, both rotor shafts are eccentrically mounted in the respective compartments, so that the blades of each shaft come nearer to the chamber wall at one point than they do at 15 another point. By this arrangement the clearance opening between the chamber wall and the working surface of the blade is constantly changing and this expedites considerably the movement of the outer edge of 20 the blade into firm biting engagement with the mass, so that the latter will be effectively held and operated upon. As the blade alternately advances toward and recedes from the chamber wall, the material is enabled to 25 work well over the blade tip into a position in which it will be effectively held by the blade itself against the chamber wall, while the blade by means of its working face is doing effective work upon such material. In the particular form shown, larger 30 clearance spaces are provided at the top of the compartments than at the bottom, but this arrangement could obviously be reversed, if desired, so as to provide larger 35 clearance spaces at the bottoms of the respective compartments. It is preferable, however, to have the larger clearances adjacent the charging opening, as shown, as 40 this facilitates the introduction of the charge. In other words, where the charging opening is located at the upper part of the compartments, the larger clearance spaces are preferably at the tops of the compartments. 45 Various changes may be made in the details of the construction herein described without departing from the scope of our invention, as defined in the claims.

We do not claim broadly herein the method 50 of mixing rubber in a mixer having a mixing chamber and rotating blades therein for working the material back and forth in said chamber, which comprises feeding rubber and powder through one end wall of the 55 mixing chamber into the vacant space at the rear of one of the blades, as claimed in our application, Serial No. 270,837; nor do we claim broadly herein the feature of arranging a rotor, for moving the material 60 back and forth, eccentrically in its chamber, whereby there is a different clearance between the blades of the rotor and the chamber wall at different points in the rotation of the rotor, as claimed in our application, 65 Serial No. 251,640.

What we claim is:

1. In a machine of the character described, a working chamber, substantially parallel rotors therein which force the material lengthwise of said chamber, said chamber having a charging opening in its end wall. 70
2. In a machine of the character described, a working chamber, a plurality of rotors therein which work the material back and forth in said chamber, said chamber having a charging opening at the end through which material is fed to said rotors. 75
3. In a machine of the character described, a working chamber, a pair of rotors in said chamber for forcing the material back and forth, and a head at the end of said chamber having a charging opening. 80
4. In a machine of the character described, a working chamber, a pair of rotors in said chamber for forcing the material back and forth, and a head at the end of said chamber having a charging opening located between said rotors. 85
5. In a machine of the character described, a working chamber, a pair of substantially parallel rotors therein which work the material back and forth, said chamber having an end wall with a charging opening above and between the rotors. 90
6. In a machine of the character described, a working chamber, a pair of substantially parallel rotors therein which work the material from one end of the chamber to the other and back again, and a detachable head on one end of said chamber having a charging opening above and between the rotors. 100
7. In a machine of the character described, a working chamber, a pair of rotors therein which force the material lengthwise of said chamber, said chamber having an end charging opening between the rotors. 105
8. In a machine of the character described, a working chamber, a pair of rotors therein which force the material lengthwise of said chamber, and a detachable head at the end of the chamber having a charging opening and a hopper associated with said charging opening. 110
9. In a machine of the character described, a working chamber, a pair of substantially parallel rotors in said chamber which work the material back and forth, and a detachable head at the end of said chamber having a charging opening located above and between the rotors, said head having a hopper associated with said charging opening. 120
10. In a machine of the character described, a working chamber, a pair of substantially parallel rotors in said chamber which work the material back and forth, and a detachable head at the end of said chamber having a charging opening located 125
- 130

- above and between the rotors, said head having a hopper associated with said charging opening, said hopper being open at the top and extending beyond the end of the 5 chamber.
11. In a rubber mixer, a working chamber, a plurality of rotary elements in said chamber having blades with front faces for mashing and mixing the material, the 10 blades of each element being arranged to work the material back and forth in said chamber and said chamber having a charging opening through which material is charged directly into the voids at the rear 15 faces of the blades of both of said elements.
12. In a rubber mixer, a working chamber, and a plurality of rotary elements in said chamber having mixing blades with working faces for mashing the material 20 against the side wall of the chamber, said chamber having an opening in its end wall through which material to be mixed is drawn by the rotating blades into the voids 25 at the rear of said blades.
13. In a rubber mixer, a working chamber, a pair of rotors therein having blades movable over the end wall of said working chamber, said end wall having a charging opening in the path of rotation of blades 30 of both rotors.
14. The method of introducing material into a mixer having a mixing chamber with a pair of bladed rotors therein, which comprises drawing material into the chamber 35 by the rotation of the blades of both rotors.
15. The method of introducing material into a mixer having a mixing chamber with a pair of bladed rotors therein, which comprises drawing material into the chamber 40 by the rotation of the blades of both rotors through one of the end walls of the chamber.
16. The method of introducing material into a mixer having a mixing chamber 45 with a pair of bladed rotors therein, which comprises drawing material into the chamber by the rotation of the blades of both rotors through one of the end walls of the chamber into vacant spaces at the rear 50 faces of blades of the respective rotors.
17. The method of introducing material into a mixer having a mixing chamber with a plurality of bladed rotors therein, which comprises feeding the material into 55 the chamber at one end thereof, so that it passes into the vacant spaces at the rear faces of the blades of said rotors.
18. The method of mixing rubber and the like in a suitable mixing chamber by means 60 of bladed rotors which work the material back and forth in said chamber, which comprises feeding material by gravity into the end of the mixing chamber between the rotors.
19. In a rubber mixer, a duplex chamber 65 having partly cylindrical compartments, and bladed rotors in the respective compartments, the blades of said rotors being eccentrically arranged with respect to said compartments to obtain a varying grip on 70 the material.
20. In a rubber mixer, a duplex chamber having partly cylindrical compartments, and bladed rotors in the respective compartments, the blades of the respective rotors 75 having different clearances at the tops of the compartments than at the bottoms thereof.
21. In a rubber mixer, a duplex chamber having partly cylindrical compartments, and bladed rotors in the respective compartments, the blades of the respective rotors having different clearances at the tops of the compartments than at the bottoms thereof, said chamber having a charging opening 80 at its end.
22. In a rubber mixer, a duplex chamber having partly cylindrical compartments, and bladed rotors in the respective compartments, the blades of the respective rotors having different clearances at the tops of the compartments than at the bottoms thereof, said chamber having a charging opening 85 at its end adjacent the points of greatest blade clearance.
23. In a rubber mixer, a duplex chamber 90 having compartments and bladed rotors in the respective compartments, the blades of said rotors having greater clearances at the tops of said compartments than at the bottoms thereof.
24. In a rubber mixer, a duplex chamber 95 having compartments and bladed rotors in the respective compartments, the blades of said rotors having greater clearances at the tops of said compartments than at the bottoms thereof, said chamber having a charging opening at the end communicating with the upper portions of both compartments.
25. In a rubber mixer, a duplex chamber 100 having partly cylindrical compartments, bladed rotors in the respective compartments and a hopper at one end of the chamber communicating with the interior of the latter.
26. In a rubber mixer, a duplex chamber 105 having partly cylindrical compartments, bladed rotors in the respective compartments, the end portion of said chamber having a charging opening and a hopper from which material moves through said opening into said compartments.
27. In a rubber compounding machine, a duplex chamber having partly cylindrical compartments in free communication 115 with each other, said chamber having a head at one end, longitudinally arranged substantially parallel rotors in the chamber located in the respective compartments, each of said rotors having blades for working the material back and forth in the corre- 120
- 130

sponding compartment, and said head having a charging opening therein through which material is introduced into both of said compartments simultaneously, as described.

28. In a rubber mixer, a duplex chamber, having partly cylindrical compartments, and bladed rotors eccentrically arranged in the respective compartments, the clearance between the rotor blades and the compartment walls being varied at different points in the rotation of said rotors.

29. In a rubber mixer, a duplex chamber, having partly cylindrical compartments, and bladed rotors eccentrically arranged in the respective compartments, the rotor blades having a greater clearance at one side of said compartments than at another side thereof.

In witness whereof, we have hereunto set our hands on the 8th day of January, 1919.

DAVID R. BOWEN.
CARL F. SCHNUCK.
